CLAIM

The ornamental design for a support stand for a motor control pendant, as shown and described.

DESCRIPTION

FIG. 1 is a perspective view of a support stand for a motor control pendant showing our new design;

FIG. 2 is a front elevational view;

FIG. 3 is a right side elevational view, the left side being a mirror image thereof;

FIG. 4 is a top plan view;

FIG. 5 is a bottom plan view; and

FIG. 6 is a rear elevational view thereof.

FIG.-1.

FIG.-3.

FIG. 4.

FIG. 5.

FIG. 2.

FIG. 6.
